CLAIM

The ornamental design for a wearable health monitoring device for personal use as shown and described.

DESCRIPTION

The present application is the U.S. designation of International Registration No. DM/225,265, filed and registered on May 30, 2022, the disclosure of which is incorporated herein by reference.

FIG. 1.1 is a top perspective view of a wearable health monitoring device for personal use showing a new design;

FIG. 1.2 is a bottom perspective view thereof;

FIG. 1.3 is a top view thereof;

FIG. 1.4 is a bottom view thereof;

FIG. 1.5 is a left view thereof;

FIG. 1.6 is a right view thereof;

FIG. 1.7 is a front view thereof;

FIG. 1.8 is a back view thereof;

FIG. 1.9 is a top perspective view shown in an environment of use;

FIG. 1.10 is a bottom perspective view shown in an environment of use;

FIG. 1.11 is a top view shown in an environment of use;

FIG. 1.12 is a bottom view shown in an environment of use;

FIG. 1.13 is a left side view shown in an environment of use;

FIG. 1.14 is a right side view shown in an environment of use;

FIG. 1.15 is a front view shown in an environment of use; and

FIG. 1.16 is a back view shown in an environment of use.

(Continued)

The broken lines in the reproductions show portions of the wearable health monitoring device for personal use and environment that form no part of the claimed design.
